UNITED STATES PATENT OFFICE.

LORENZO ULLO, OF NEW YORK, N. Y.

CAR-VESTIBULE.

No. 886,744.

Specification of Letters Patent.

Patented May 5, 1908.

Application filed January 23, 1908. Serial No. 412,323.

To all whom it may concern:

Be it known that I, LORENZO ULLO, a citizen of the United States, residing at New York city, in the county of New York and State of New York, have invented certain new and useful Improvements in Car-Vestibules, of which the following is a specification.

My invention relates to doors for railway cars and the like, and its novelty consists in the construction and adaptation of the parts as will be more fully hereinafter pointed out.

It is difficult, in cases where the passengers are obliged to leave and enter from the same end of a railway car to induce them to avoid moving in conflicting columns, or to move rapidly either to leave or enter the car. It is the purpose of my invention to overcome this difficulty, and, in brief, I do so by providing the car vestibule with two doors folding inwardly so as to leave two openings in the side of the car body and providing also a transversely movable partition of less width than the distance between the outer edges of the folding doors and the opposite side of the car, and which partition is normally placed toward the opposite side of the car, but is so connected by means of suitable mechanism with the folding doors that when the partition is moved toward the center of the car it affords a barrier against passage at that point, but will permit a passage between its edge opposite the open door and the other side of the car, so that there is in effect formed two passage ways—one nearest to the body of the car, whereby the passengers may readily leave the car—and another on the other side of the open doors whereby they may readily enter and are guided past the outer edge of the movable partition into the body of the car.

Figure 1 is an elevation of the door and the movable partition when the latter is in the center of the car. The car body being shown in section and the view being taken in front of the plane of the line 1—1 in Fig. 2. Fig. 2 is a top plan view of the folding doors, the movable partition and their connections, the car body being shown in section. Fig. 3 is a view similar to Fig. 2 with the movable partition being shown in its normal position and the doors being closed. Fig. 4 is a detail taken in section on the plane of the line 4—4 in Fig. 1.

In the drawings, 10 is the body of the car

which is extended to form a vestibule in the usual manner. Depending from the roof 11 are hangers 12 supporting a rail 13 adapted to afford a track for the rollers 14 rotating in bearings formed in supporting plates 15 arranged in pairs and secured on opposite sides of a movable partition 16 which is adapted freely to move to and fro as it is slid along the rail 13, the extent of its movement being limited by the position of the hangers 12. The upper edge of this partition 16 is provided with two upwardly extending studs or pins 17 and 18 adapted to engage with projections on the push rod 30 hereinafter referred to.

Arranged at the side of the car are two doors 20, each provided with a lower pivot 21 and an upper pivot 22 engaging suitable bearings in the body of the car, so that each door will revolve on these pivots and the two doors together form a pair of folding doors opening inwardly into the vestibule. Jambs 23 and 24 are provided in the car body to engage the doors 20 at their outer edges and partitions 25 and 26 are arranged to meet the doors at their inner edges in order to seal the openings closed thereby. Each door 20 is provided at its upper rear edge with a rearwardly extending bracket 27 hinged to a link 28 pivoted to a second link 29 which is pivoted in turn to a push rod 30 which is provided with extensions 31 running between guides 32 depending from the roof 11. The other end 33 of the push rod is bent over and downward to form a hook adapted to cooperate with the stud 18 on the partition 16. The push bar 30 is also provided with a projection 34 similarly adapted to cooperate with the stud 17 on the partition 16. Rollers 19 on each side of the push rod 30 and revolving in bearings in the frames 15 serve to keep the parts in alinement.

The method of using the device is as follows: Supposing the parts to be in the position shown in Fig. 3, it will be observed that the folding doors 20 are closed and the movable partition 16 is at the right hand side of the vestibule. I have designated the central space immediately to the left of the partition 16 by *x*. The doorway adapted to be closed by one of the doors 20, as *y*; the doorway adapted to be closed by the other door 20, as *z*, and the space opposite the partition 16, as *w*. It will be noted that when the parts are arranged, as shown in Fig. 3, the

space x to the left of the partition 16 is entirely free and the passengers can move through the center of the car from one vestibule to the vestibule of the adjacent car. 5 When a station is reached the partition 16 is moved to the left by the guard, or other employee, until it reaches a central position at x , as shown in Figs. 2 and 3. However, in moving it the stud 17 has engaged the projection 34 on the push rod 30, has moved the push rod to the left or toward the left side of the car, and through the levers 29 and 28 has caused each of the folding doors 20 to swing inwardly upon their respective pivots 21 10 and 22 to assume the positions shown in Figs. 2 and 3; that is, both doorways y and z which were previously closed by these doors 20 are opened. The passengers moving toward the front part of the car find the movable partition 16 immediately in front of them at x , closing the passageway to the next adjacent car, and right in their way and they naturally move toward the left and out of the open doorway y . The incoming passengers 15 on the platform to the left of the vestibule seeking to enter the car find their ingress blocked by the outgoing crowd and do not attempt to enter the doorway y , but naturally enter the doorway z which is open, and 20 they readily and instinctively move through said doorway into the vestibule in front of the doors 20 and the partition 16 and in the direction indicated by the arrow in Fig. 2, and so through the space w into the car. 25 The partition 16 is then moved again to the left by the guard and when the stud 18 engages the hook 33 on the push rod 30 the latter is moved to the left and through the action of the links 28 and 29 the folding doors 30 are closed by the time the partition 16 reaches the end of its travel. It is obvious 35 that this arrangement can be duplicated on the right side of the car with a second partition 16 moving adjacent to the first one 40 and that the operation of the parts will be precisely the reverse of the parts which have been described.

What I claim as new is:—

1. The combination with the body of a 50 railway car, or the like, of a movable partition, two doors, each adapted to close openings in the car body and connections between the partition and the doors whereby the movement of the partition will automatically 55 actuate the doors.

2. The combination with the body of a 60 railway car, or the like, of a transverse movable partition, two doors adapted to close openings in the body of the car, and a connection between the partition and each door whereby the movement of the partition will automatically simultaneously open and close both doors.

3. The combination with the body of a 65 railway car, or the like, of a partition nor-

mally placed so that it will not obstruct the center of the car, means for moving the partition, two doors adapted to close openings in the car body, and connections between the partition and both doors whereby when the partition is moved from its normal position both doors are opened inwardly. 70

4. The combination with the body of a railway car, or the like, of a partition normally placed away from the center of the car, means for moving the partition, two doors adapted to close openings in the car body, a connection between the partition and each door whereby when the partition is moved to the center of the car both doors are opened inwardly to afford openings in the car on each side of the partition. 80

5. A car vestibule provided with a transversely placed movable partition, two folding doors adapted to open inwardly, mechanism connecting the partition to each door whereby when the partition is moved toward the center of the car the doors are opened, and when it is moved in the opposite direction they are closed. 85

6. A car vestibule provided with two folding doors rotating inwardly so that they are back to back when opened, a transversely movable partition of substantially the same width as the doors normally placed at the side of the car, means for moving the partition laterally, and connections between the partition and the doors whereby when the partition is moved to the center of the car the doors are automatically opened and a passage 90 way is left between the partition and the side of the car opposite the doors. 95

7. A car vestibule provided with two openings, a door adapted to close each opening, supports on which the doors are 100 adapted to revolve, a transversely placed partition of less width than the distance between the outer edges of the doors, when opened, and the opposite side of the car, a rail on which the partition is adapted to slide, a rod actuated by the movement of the partition, and connections between the rod and the outer edge of each door whereby the doors are revolved on their supports. 110

8. A car vestibule provided with two 115 openings, a door adapted to close each opening, supports on which the doors are adapted to revolve, a transversely placed partition of less width than the distance between the outer edges of the doors, when opened, and the opposite side of the car, a rail on which the partition is adapted to slide, a rod actuated by the movement of the partition, and connections between the rod and the outer edge of each door whereby the doors are 120 revolved on their supports, and means for limiting the extent of movement of the partition. 125

9. A car vestibule provided with a rail, a partition provided with rotating members 130

adapted to move on said rail, a pair of doors vertically hinged and adapted to fold inwardly, a push rod, jointed connections between the doors and the rod and projections on the rod adapted to engage with projections on the partition to move the push rod when the partition is moved.

In testimony whereof I affix my signature in presence of two witnesses.

LORENZO ULLO.
